UNITED STATES PATENT OFFICE.

ORLANDO GIANNINI, OF AUSTIN, ASSIGNOR TO THE UNITED STATES AUTOMATIC PERFUMERY COMPANY, OF CHICAGO, ILLINOIS.

DESIGN FOR A STANDARD FOR PERFUMERY-VENDING APPARATUS.

SPECIFICATION forming part of Design No. 20,721, dated May 12, 1891.

Application filed March 10, 1891. Serial No. 384,494. Term of patent 7 years.

To all whom it may concern:

Be it known that I, ORLANDO GIANNINI, a citizen of the United States, residing at Austin, in the county of Cook and State of Illinois, have invented a new and useful Design 5 for an Ornamental Standard for a Vending-Case, of which the following is a specification.

My design relates to an ornamental standard for a coin-operated perfumery-vending apparatus.

In the accompanying drawing my design is represented by a view in perspective.

The design comprises the base of the standard in the form of the case of rectangular outline, an upwardly-tapering stem surmount-

ing the case and having its surface provided with ornamental work, the ornamented stem describing a graceful overhanging curve toward its upper end, and from the extremity 20 of the curve extends the representation of a group of ornamental bells, of which two smaller are shown as flanking a central larger one, the relative disposition of the bells causing them to create the impression of ringing. 25

What I claim is—

The design for an ornamental standard for a vending-case, as herein described and shown.

ORLANDO GIANNINI.

In presence of—

J. W. DYRENFORTH,
M. J. FROST.
